UNITED STATES PATENT OFFICE.

PAUL HEYLANDT, OF BERLIN-SUDENDE, GERMANY.

DEVICE FOR DEVELOPING GAS UNDER PRESSURE FROM LIQUEFIED GASES.

Application filed January 3, 1921. Serial No. 434,823.

To all whom it may concern:

Be it known that I, PAUL HEYLANDT, a citizen of the German Republic, residing at Berlin-Sudende, Germany, have invented 5 certain new and useful Improvements in Devices for Developing Gas Under Pressure from Liquefied Gases, of which the following is a specification.

This invention relates to a device for supplying industrial establishments with large quantities of oxygen or other liquefiable gases without involving the carriage of steel cylinders or bottles, and for developing gas under pressure from liquefied gases, the 15 principal object of the invention being to provide an apparatus in which the liquefied gas may be stored and transported for long distances and the gas delivered under pressure automatically generated within the apparatus.

It has heretofore been considered impossible to make vessels capable of containing several thousand litres of liquids, the temperatures of which are as low as those 25 of liquid oxygen, nitrogen etc., sufficiently proof against the reception of warmth from without and against the evaporation losses entailed thereby, and at the same time to make their resistance to pressure such 30 that they would withstand a pressure as high as that required for autogenous cutting, i. e. a pressure of 8 atmospheres or more. One of the objects, therefore, of the present invention is to provide a comparatively simple device which is sufficiently 35 protected against loss of cold and is strong enough to hold three hundred to several thousand kilograms of liquefied gas and to resist an internal pressure of over fifteen 40 atmospheres, whereby industrial establishments may be supplied with large quantities of liquefied gases which can be taken in gaseous form, and at the required operating pressure, directly from the vessel in which 45 it was transported, without the aid of discharging compressors.

The drawings accompanying and forming part of this specification illustrate diagrammatically a vertical section of an apparatus 50 constructed in accordance with the present invention.

The vessel consists of an internal vessel *h* of metal into which the liquid oxygen is introduced through the inlet valve *b* from an 55 air-liquefying apparatus (not shown). During the inflow of the liquid oxygen the

valves *d* and *a* have to be kept open. The internal vessel *h* is fixed in the middle of the enveloping vessel *l*. The space between *h* and *l* is filled with a non-oxidizable substance such as slag-wool. By using slag-wool as an insulating material the evaporation of the liquid oxygen etc. is sufficiently reduced for practical purposes. *a* is a discharge valve through which liquefied gas 60 may be taken from the reservoir *h*. When liquefied gas is to be extracted, the discharge valve *a* is opened and the valves *b*, *c*, *d* and *e* are kept closed. To take non-compressed gas from the vessel, the valves *a* and *d* are 65 both opened, while the valves *b*, *c* and *e* are closed. Finally, gas at a pressure up to several atmospheres can be discharged by opening *c* and *e* while keeping *a*, *b* and *d* closed. In the instance last mentioned the liquefied 70 gas rises through the ascension pipe in the vessel *h* to the valve *c* and flows through, and evaporates in, the the evaporating coil *i* which consists of one or two spirals and lies 75 adjacent to the inner or outer surface of the enveloping vessel *l*. The liquefied gas can be taken in a gaseous state in any desired quantitites at the required working pressure (2 to 15 atmospheres) from the valve *e*. By providing two valves *c* and *e* through 80 which the fluid flows one after the other in the same direction, *c* being passed chiefly by liquid and *e* only by gas, the working pressure can easily be regulated.

The cold liberated during evaporation is 85 transferred by the coil *i* to the envelope *l* and the insulating substance *k* in the space between the outer and inner vessels and is thus stored in the non-oxidizable insulation 90 during the time in which the pressure is produced. By this storage of cold in the 95 slag-wool the evaporation of oxygen that subsequently takes place when the operations are stopped is considerably reduced. A pressure gauge *f* and a safety valve *g* 100 are connected to the gas space above the liquid.

The whole equipment is adapted to be used both as a stationary storage vessel and as a carrying vessel for large quantities of 105 liquid oxygen etc., and especially as a supply vessel for delivering gas at any desired operating pressure up to 15 and more atmospheres.

If the vessels constructed according to the 110 present invention are used as stationary storage vessels, the equipment will be an effec-

tive substitute (permitting of divers uses) for the large gas storage vessels or so-called gasometers now generally used for oxygen, nitrogen, hydrogen because, while taking up 5 much less space, the equipment has a capacity which, in conformity with the respective volumes of the gases in their liquefied and gaseous states, is about 800 times as great; for one litre of liquid oxygen when 10 evaporated to a gas of atmospheric pressure will make at 0° or 14° or 27° about 790, 830 or 870 litres respectively of oxygen gas. The corresponding figures for a litre of liquid nitrogen are 640, 670 or 700 litres of nitrogen gas.

For the same reason the apparatus will, when used as a carrying vessel, save the greatest part of the freight charges incurred by sending compressed gas in steel bottles.

Again, if the new process is employed for the production of gas under pressure the same vessel which was first used at the gas producing factory for gathering the liquefied gas, as for example the liquid oxygen, 25 and then served as a carrying vessel, will also serve as an automatic gas producing plant at the point of consumption.

When used for this purpose the vessel, after its arrival at the place of consumption, 30 is first connected to the gas consuming apparatus, say, to the autogenous welding and cutting apparatus. The valve *e* is opened only when, by the automatic evaporation of the liquid oxygen, the pressure in the interior vessel has risen to the pressure required for operation. The excess of pressure is reduced and maintained at the proper operating pressure by corresponding adjustments of the valves *c* and *e*. If gas is to 35 be supplied at several points of operation at different pressures a corresponding number of reduction valves are provided in the supply pipe behind the valve *e*. By this arrangement the carrying about of steel bottles containing highly compressed gas is rendered unnecessary in the establishment where the gas is used.

Another advantage offered by the present construction is that the evaporation of the liquid oxygen, nitrogen, air etc. diminishes 50 when a greater pressure is exerted upon it, because as the pressure increases the boiling point of the liquefied gas rises and hence the difference between the raised boiling point and the external temperature is decreased. This fact, together with the fact that the outlet valve *e* is located in the warmest zone, causes the flow of gas to be uniform and at a uniform pressure. In 55 other words, as soon as the pressure within the vessel *h* has, owing to the natural evaporation of the liquefied gas, risen to the desired operating pressure, the valves *c* and *e* are opened sufficiently to deliver the gas at 60 the same pressure, it being understood that

when passing through valve *c* it is still almost entirely in liquid form. However, as it begins to ascend through the coil it will become more and more gaseous until it reaches the warmest zone wherein the valve *e* 70 is located, at which time the fluid is entirely gaseous. The continued evaporation maintains the liquid in the vessel *h* at a uniform pressure as long as the valves *c* and *e* are adjusted for that pressure, provided that 75 the operation is not started until the desired pressure is reached within the vessel *h*. Any tendency to undue increase in pressure is offset by the continually enlarging space 80 above the liquid in the vessel *h* due to the escape of gas through the valve *e*, and to the fact above stated, that as the pressure increases evaporation decreases, and inasmuch as the pressure is produced by evaporation, with any material increase in pressure there must come a time when there is practically no evaporation, and therefore the pressure ceases to rise. Furthermore, at the close of operations sufficient cold has 85 been transferred to the insulating material by the expansion of the gas in the coils *i* to prevent any substantial evaporation in the vessel *h*, thereby preventing any dangerous rise in pressure when the apparatus is 90 not in use.

The novelty of the process and its technical advantages for industrial purposes may be epitomized as follows:

In the gas-producing factory, as in the oxygen factory, the oxygen is no longer produced in a gaseous form but in a liquid form and sent in this state over long distances to the consumer where it is converted into gas of a sufficient operating pressure and consumed. By this means the high cost of the 100 large gas vessels, gas meters, filling compressors, and steel bottles, in addition to the operating cost, are saved, and on account of the great reduction of space and weight the current cost of freight amounts to less than one half of the cost of the carriage of the 105 steel bottles employed hitherto.

I claim:

1. A portable device for storing and transporting liquefied gas, comprising an internal metal vessel adapted to hold a liquefied gas, an envelope of insulating material adapted to prevent the radiation of cold from, and the absorption of warmth by, the said vessel, an inlet for introducing liquefied gas into the vessel, a charging valve controlling the said inlet, a discharge pipe leading from the said vessel to the exterior, a discharge valve controlling the discharge pipe, a passage leading from the vessel into the discharge pipe, and a valve controlling the said passage.

2. A portable device for storing and transporting liquefied gas, comprising an internal metal vessel adapted to hold a 115

liquefied gas, an envelope of insulating material adapted to prevent the radiation of cold from, and the absorption of warmth by, the said vessel, an inlet for introducing liquefied gas into the vessel, a charging valve controlling the said inlet, and means for discharging the liquefied gas in a gaseous state at a high pressure consisting of a passage leading from the interior of the vessel and lying adjacent to the said envelope, a valve at the beginning of the said passage and a valve at the end of the said passage.

3. A portable device for storing and transporting liquefied gas, comprising an internal metal vessel adapted to hold a liquefied gas, an envelope of insulating material adapted to prevent the radiation of cold from, and the absorption of warmth by, the said vessel, an inlet for introducing liquefied gas into the vessel, a charging valve controlling the said inlet, a discharge pipe leading from the said vessel to the exterior, a discharge valve controlling the discharge pipe, a passage leading from the vessel into the discharge pipe, a valve controlling the said passage, and means for discharging the liquefied gas in a gaseous state at a high pressure consisting of a passage leading from the interior of the vessel and lying adjacent to the said envelope, a valve at the beginning of the said passage and a valve at the end of the said passage.

35 4. A device for supplying and automatically generating gas at a predetermined operating pressure comprising an internal metal vessel adapted to hold a liquefied gas, a charging inlet for introducing the liquefied gas into the said vessel, an envelope of insulating material adapted to prevent the radiation of cold from, and the absorption of warmth by, the said vessel, and means for discharging the gas in a gaseous state at the required operating pressure after the pressure in the vessel has risen to said operating pressure by evaporation of the liquefied gas, said means comprising a discharge passage leading from the interior of the vessel and winding round the said envelope, and valves at the beginning and end of the said passage for regulating the pressure of the gas at the point of discharge.

50 5. A device for supplying and auto-

matically generating gas at a predetermined 55 operating pressure comprising an internal metal vessel adapted to hold a liquefied gas, a charging inlet for introducing the liquid gas into the said vessel, an envelope of insulating material adapted to prevent the 60 radiation of cold from, and the absorption of warmth by the said vessel, and means for discharging the gas in a gaseous state at the required operating pressure after the pressure in the vessel has risen to said 65 operating pressure by evaporation of the liquefied gas, said means comprising a discharge passage leading from the interior of the vessel and winding round the said envelope, valves at the beginning and end 70 of the said passage for regulating the pressure of the gas at the point of discharge, a by-pass for leading the gas from the vessel into the said discharge passage, 75 and a valve controlling the said by-pass.

6. A device for supplying and automatically generating gas at a predetermined operating pressure comprising an internal metal vessel adapted to hold a liquefied gas, a charging inlet for introducing the liquefied gas into said vessel, an envelope of insulating material adapted to prevent the radiation of cold from, and the absorption of warmth by the said vessel, and means for discharging the gas in a gaseous state 80 at the required operating pressure after the pressure in the vessel has risen to said operating pressure by evaporation of the liquefied gas, and for transferring the cold of the liquid and evaporating gas to the 85 envelop of insulating material, said means comprising a spiral pipe leading from the said vessel and passing adjacent to the said envelope, substantially as described.

7. In combination with a device of the 90 kind described in claim 2, a distributing pipe connected to the discharge passage, and reduction valves for supplying gas simultaneously at various pressures from the said distributing pipe.

In testimony whereof I have signed this specification in the presence of two witnesses.

PAUL HEYLANDT.
